United States Patent Office

Des. 211,426
Patented June 11, 1968

211,426

AIRCRAFT

Theodore R. Smith, Los Angeles, Calif., assignor to Ted Smith Aircraft Co., Inc., Northridge, Calif., a corporation of California

Filed Aug. 11, 1966, Ser. No. 3,426

Term of patent 14 years

(Cl. D71—1)

FIG. 1 is a top plan view of an aircraft showing my new design;

FIG. 2 is a front elevation thereof with the propeller blades shown in an alternate position to that shown in FIG. 1;

FIG. 3 is a rear view thereof with the propeller blades shown in an alternate position to that shown in FIG. 1.

FIG. 4 is a bottom view thereof; and

FIG. 5 is a side view thereof.

The side of the aircraft not shown in the drawing is substantially as illustrated in FIG. 5.

I claim:

The ornamental design for an aircraft, substantially as shown and described.
